UNITED STATES PATENT OFFICE.

GEORGE W. HODGES, OF MORGAN PARK, ILLINOIS, AND GLOVER S. HASTINGS, OF PLAINVILLE, CONNECTICUT.

FASTENING FOR KNIFE-HANDLES.

SPECIFICATION forming part of Letters Patent No. 769,220, dated September 6, 1904.

Application filed October 12, 1903. Serial No. 176,599. (No model.)

To all whom it may concern:

Be it known that we, GEORGE W. HODGES, residing at Morgan Park, in the county of Cook and State of Illinois, and GLOVER S. HASTINGS, residing at Plainville, in the county of Hartford and State of Connecticut, citizens of the United States, have invented certain new and useful Improvements in Fastenings for Knife-Handles, of which the following is a specification.

This invention relates to knife-handles, and has for its object to produce a handle for knives, forks, spoons, or other tools of sanitary construction at a low cost and having strength, durability, and beauty.

In the drawings accompanying and forming part of this specification, Figure 1 illustrates a side view, partly in section, of a knife embodying our improvements. Fig. 2 represents a longitudinal edge view of the same. Fig. 3 is a detail view of the rearward portion of a handle adapted to receive our improved heel-cap, as hereinafter set forth. Fig. 4 is a detail side view of a knife-blade having its rearward or handle end of a suitable shape to be attached to a handle in accordance with our invention. Fig. 5 shows front and rear views of the blade thimble or socket; and Fig. 6 is an enlarged longitudinal sectional view on line *aa* of Fig. 1 of a portion of the blade and handle, showing the method of fastening one to the other.

In the several figures similar parts are designated by similar characters of reference.

For the main part of the handle 1 we preferably employ glass or some other vitreous composition; but other molded materials can be used with equal efficiency in some forms of knives or tools, as can also wood, metal, ivory, or other substances suitably carved or pressed into the requisite shape. Said handle 1 is necked down or reduced in size at its forward or blade end, and on such reduced portion are formed protuberances 15, preferably of button or hemispherical shape, but which may with equal usefulness be in the form of mutilated ribs lying either lengthwise or crosswise of the handle. Said protuberances form hollows or depressions between them. The

object of these protuberances and depressions is primarily to anchor the thimble 3 securely to the knife-handle by means hereinafter set forth and also to locate the inner surface of the sleeve portion of said thimble 3 at a uniform distance from the surface of the end 2 of the knife-handle when in place on said handle. It is also obvious that depressions or grooves in the end 2 of the knife-handle and inwardly-extending protuberances inside the thimble 3 would in some forms of knives answer the requirements equally well.

In Fig. 3 at the rearward end of the handle is shown a reduced portion 4, which portion is provided with nicks or undercut depressions 5, whose function is that of retaining-points for a cap 7, of metal or of some plastic material, which construction is one of the features of our improvement.

At 6 is shown a sprue or portion of a casting-gate, whose juncture with the end 4 of the handle 1 will form other retaining means for said cap 7. Said sprue 6 is to be broken off approximately on the line *bb*, and which ragged break will furnish other more or less efficient retaining-points for said cap 7.

The thimble or socket (shown most fully in Fig. 5) may be of any desired construction as to general shape and is provided with lips or ears 8 suitable to engage and hold the opposite sides of the blade-shank 11 and with an opening or slot 9 to admit the horns 12 of said shank 11. The slot 9 may be made shorter than the extreme distance across the horns 12, the shank 11 being hooked into said slot one horn at a time and then held firmly between the end 2 of the handle and the inner wall of the thimble adjacent to the ends of the slot 9, thus forming an exceptionally rigid construction.

After the blade 10, thimble 3, and handle 1 have been assembled they are put into a suitable mold and a metal or alloy of requisite hardness and fusible at a comparatively low temperature is poured into the mold and flows or is forced around both the inside and outside of the thimble 3, thereby locking the handle, sleeve, and blade securely to one another and forming a finishing-cover and re-

inforcing-envelop 13, 13^a, and 13^b about the blade, shank, thimble, and handle end.

This improved construction leaves no opening between the blade and handle to catch dirt of any kind, and thereby provides a cleanly and sanitary article of pleasing appearance and durability.

The cap 7 for the rearward end of the handle may be cast on in a manner similar to that employed for the forward end. It is also obvious that materials other than metal may be used for the caps 7 and 13 and for locking the blade, thimble, and handle together. Various kinds of cement or other plastic material that would be of requisite hardness after setting may be employed. Neither do we limit our invention to the specific construction shown and described herein, but reserve to ourselves the right to vary said construction within the spirit of our invention.

Having thus described our invention, we claim—

1. A handle, a thimble, a blade, said handle having at its blade end a reduced portion, said 25 reduced portion provided with laterally-projecting protuberances adapted to contact with the inner wall of the thimble and means interlocking said handle, thimble and blade.

2. A handle, a blade having horns at the handle end thereof, an integral thimble of 30 metal having blade-supporting ears at one end thereof, and between said ears a blade-slot whose length is less than the distance across the horns of the blade, and means interlocking said handle, thimble and blade.

3. A handle, a blade, a thimble connecting said handle and blade and interlocking means between said thimble and handle interlocking said handle blade and thimble, and means exterior of said thimble interlocking said blade, 40 thimble, and first interlocking means.

4. A device of the class specified comprising a blade of metal, a thimble of metal, a handle of glass, and metallic means completely filling the space between the thimble and 45 handle, and interlocking said blade, thimble and handle, and metallic means exterior of said thimble interlocking said blade, thimble and first interlocking means and sealing all junctures of blade thimble, handle and first 50 interlocking means.

GEORGE W. HODGES.
GLOVER S. HASTINGS.
